(57) **CLAIM**

The ornamental design for an enemator with tube, as shown and described.

DESCRIPTION

FIG. 1 is a perspective view of an enemator with a tube, showing the new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

(Continued)

The enemator with tube is shown with a symbolic break in its length. The appearance of any portion of the article between the break lines form no part of the claimed design. The broken lines illustrate portions of the enemator with tube that do not form any part of the claimed design
